CLAIM

The ornamental design for a hollow round urban terrorism traffic barricade, as shown and described.

DESCRIPTION

FIG. 1 is a top perspective view of a hollow round urban terrorism traffic barricade showing our new design, including a molded plastic body with an inlet disposed on the top side for filling the hollow round urban barricade terrorism with water, and one recessed area in the top side to accommodate plants or other decoration;

FIG. 2 is a front elevation view thereof;

FIG. 3 is a rear elevation view including an outlet on the lower portion to drain water from the hollow round urban terrorism traffic barricade;

FIG. 4 is a side elevation view thereof;

FIG. 5 is a top elevation view thereof;

FIG. 6 is a bottom elevation view thereof; and,

FIG. 7 is a perspective view showing the bottom, side, and recessed cavity; and,

FIG. 8 is a bottom perspective view thereof.
